(57) **CLAIM**

The ornamental design for a dental matrix device, as shown and described.

DESCRIPTION

FIG. 1 is an upper perspective view of an embodiment of a dental matrix device;

FIG. 2 is a lower perspective view of the dental matrix device of FIG. 1;

FIG. 3 is a rear view of the dental matrix device of FIG. 1; FIG. 4 is a front view of the dental matrix device of FIG. 1; FIG. 5 is a right side view of the dental matrix device of FIG. 1;

FIG. 6 is a left side view of the dental matrix device of FIG. 1; and,

FIG. 7 is a top view of the dental matrix device of FIG. 1, which is identical to a bottom view of the dental matrix device of FIG. 1.

In the drawings, the broken lines depict environmental subject matter only and form no part of the claimed design.

1 Claim, 6 Drawing Sheets
